United States Patent Office.

THOMAS C. MARSHALL AND H. W. HAWKINS, OF AKRON, OHIO.

Letters Patent No. 91,649, dated June 22, 1869.

IMPROVEMENT IN WHEEL-MAKING MACHINE.

The Schedule referred to in these Letters Patent and making part of the same.

Know all men by these presents:

That we, THOMAS C. MARSHALL and H. W. HAWKINS, both of Akron, in the county of Summit, and State of Ohio, have invented certain new and useful Improvements in Wheel-Making Machines; and we do hereby declare that the following is a full, clear, and exact description of the same, reference being had to the accompanying drawings, forming a part of this specification, in which—

Figure 1 represents a front view of our improved wheel-machine, portions of the frame being broken off to show the parts beyond;

Figure 2 represents a plan view of the same, portions being broken off to show the parts beneath;

Figure 3 represents a section on line A B, fig. 1, looking as indicated by the arrow;

Figure 4 represents a section on line C D, fig. 1;

Figure 5 represents a section on line E F, fig. 2, showing the cutter-head, for backing off spokes;

Figure 6 represents a horizontal section of the self-centring chuck, on line G, fig. 3;

Figure 7 represents a front view of the self-centring chuck, and device used for boring felloes; and

Figure 8 represents a plan view of the felloe-block and gauges, when in position for boring.

To enable those skilled in the art to which my invention belongs, to make and use the same, I will proceed to describe it more in detail.

The nature of my invention consists—

First, in the peculiar construction of the self-centring chuck A, as hereinafter described, for holding the hub.

Also, in the combination, with the self-centring chuck, and devices for operating the same, of the mechanism for cutting the box-seats, as hereafter set forth.

Also, in the combination of certain devices for cutting off the spokes at the required length, and forming the tenons at their ends, as hereafter explained.

Also, in the combination, with the self-centring chuck or other suitable device, of a device for holding and gauging the felloes during the operation of boring the same, as hereafter explained.

Also, in a peculiar-constructed gauging-device, to facilitate the proper boring of the felloes, as hereafter set forth.

Also, in the mechanism for backing off spokes, boring dowel-pin holes in the ends of felloes, and for other purposes, as hereafter described.

Also, in the peculiar construction of certain devices, hereinafter described, and in the combination of said devices, to be used in a power-machine, to facilitate the manufacture of wheels for carriages, and other purposes, as hereafter explained.

In the drawings—

The parts marked A constitute the main frame, upon which are arranged the different parts of the machine, as follows:

At the front of the frame A, secured thereto, and firmly braced, is a table, B, projecting forward, and having in its centre a circular opening, around which, upon the top of the table, is placed a circular self-centring chuck, for holding hubs while cutting the seats for the boxes.

The chuck is formed with a bottom rim, b, secured firmly to the table B, and having upon its upper side three pairs of guide-blocks, c, and between each pair work dogs d, as indicated in the drawings.

The dogs d are all directed towards one common centre, and are furnished at their inner ends with double points, so that they will retain a firm hold.

The dogs d are moved back and forth by means of curved ribs e, which fit into and slide in grooves formed in the tops of the dogs d, near their outer ends, as indicated in the drawings, fig. 6.

The curved ribs e are fastened eccentrically to the under side of the top rim e of the chuck, and rest upon the tops of the guide-blocks c, thereby supporting the top rim e, which can be moved round by means of the handle f, carrying the ribs e to the position shown in red lines, fig. 6, which advances the dog d equally towards the centre.

A pin, f', is placed in the under side of the top rim e, to prevent its swinging too far round.

The top rim is kept in place by clasps or hooks g, which project upward from the guide-blocks, and turn at a right angle over the edge of the rim e.

Below the table B is an upright spindle, C, having at its upper end a cutter-head, D, which carries the cutters o, for forming the box-seat at the inner end of the hubs.

The spindle C is supported upon a step, a', connected by a bolt, or pin, 23, to the end of the lever a, near the lower part of the machine, by which it can be raised or lowered, and turns in bearings B', upon projections of the frame A.

Above the table B is another upright spindle, E, with a cutter-head, g, at its lower end, which carries the cutters o' for cutting the box-seats in the outer end of the hubs.

The spindle E turns in bearings h, upon projecting portions of the upright frame A'. It is supported and operated up and down by a lever, F, which has attached to its forward end a fork, i, which fits into a groove formed in the upper end of the spindle E; also, a metallic plate, j, that rests upon the top of the spindle E, and forms a bearing when the lever F is pressed down.

The lever F is pivoted at its rear end to the standard g' upon the upright frame A', and its forward end, in connection with the upright spindle E, is held in an elevated position by a coiled-wire spring, k, placed around the upper end of the spindle E, above its top bearing h, and acting on the fork i of lever F by its expansive force.

The lever F is connected by a cord, chain, or rod, b', to the lever a at the lower part of the machine, by means of which the upper spindle E can be depressed, and the lower spindle C raised at the same time, by pressing the foot upon the treadle G, to which the rear end of lever a is joined by the connection G', as fully indicated in the drawings.

The motion is imparted to the spindles C and E through their pulleys C' and E', by belts I, from pulleys I' upon the upright shaft H, at the back of the machine, one of the belts I being crossed for the purpose of driving the cutter-heads D and g in opposite directions.

The upper end of the upright shaft H runs in a bearing, h', on the frame A, and its lower end on a step, l, projecting from the main frame A.

It has near its lower end a driving-pulley, H', fitted loosely upon the shaft, and supported by a movable collar, which is attached, by means of the fork m, to the rear end of a long lever, J, pivoted to the main frame at m', and extending to the front of the machine, and by which the pulley H' can be raised or depressed.

At the top end of the hub of the pulley H', are formed notches, which, as the pulley is raised, engage with pins fixed in the shaft H, thereby turning the shaft H, and other parts of the machine belted thereto, but when the pulley is depressed, the notches fall below the pins, and the shaft H is not acted upon.

The pulley H' is retained in a raised position by means of the right-angled catch J', which holds down the end of lever J.

Motion is transmitted to pulley H' from pulley 4, upon the main shaft K, by means of a belt, L.

The cutter-heads D and g are made hollow, and have threads cut on their inner surfaces, to fit into similar threads cut on the ends of the spindles C and E, upon which they are screwed, rings or flanges being made upon the spindles, to prevent them from entering the heads too far.

Rings, or flanges, n n', are also formed around the cutter-heads D and g, that strike the ends of the hubs when the box-seats are cut to the required depth, and prevent the cutters from entering further.

The main shaft K extends the length of the main frame A, upon the lower part of which it is supported and turns in suitable bearings. It is provided with a loose pulley, 1, and driving-pulley 2, through which the power is applied to the machine, and also with other pulleys, 3, 4, 5, and 6, for transmitting motion to the other parts of the machine, as hereafter explained.

At the left-hand end of the main frame A, is a table, M, having in its central part a slot, through which passes the shank of the centre-pin p, and the bolt o that holds the chuck-seat N, both being secured at the under side of the table M, by the nuts p' and N'. Metallic plates d and d' are arranged at each side of the slot, to prevent too rapid wearing of the parts.

The chuck-seat N is formed to receive a chuck like the one on the table B, for the purpose of holding the wheels in a horizontal position upon the table M, or they may be placed on the centre-pin p, which is used for the same purpose.

At the top of the main frame A, near the left-hand end of the machine, is a platform, P, upon which the spokes of the wheels rest, while they are being sawed off, and their tenons formed.

The spokes are held in position, while cutting the tenons, by a hand-lever, P', fastened at its rear end to the back part of the platform P by a swivel, q.

The hand-lever P' has in its lower side a notch, r, which fits the spokes, and by pressing it down upon them, they are prevented from slipping either way.

At the right-hand edge of the platform P is arranged

a circular saw, S, upon the end of an arbor, Q, which runs in bearings s, supported by the frame R, and which is driven by the belt Q' from pulley 6, upon the main shaft K.

The frame R is hinged to the top rail of the main frame A, at the back of the machine, and can be raised to bring the saw S into working-position, and lowered to carry the saw S out of the way, when the hollow auger T is to be used for cutting the tenons at the ends of the spokes, to receive the felloe.

The shank of the hollow auger T is fitted into the end of an arbor, T', and is secured by a set-screw, v. The arbor T' runs in bearings s', supported in a similar manner to those of the saw-arbor by the frame R', hinged to the main frame A, at the back of the machine, by the hinges x, whereby the auger T may be lowered, as indicated by red lines in fig. 3 of the drawings.

A gauge-collar, t, is placed upon the arbor T', that strikes against the side of the bearing s' as the auger is moved forward, and regulates the length of the tenon cut.

The arbor T' has upon it a pulley, U, and is driven by a belt, U', from pulley 5 upon the main shaft K.

At the opposite end of arbor T' from the auger T, is arranged a lever, V, extending across the machine, its rear end secured to the upright frame A by a strip of metal, t', and its front end fitted to slide in a horizontal groove in the guide-block V. It is connected to the end of the arbor T' by a metallic plate, w, the edges of which are bent over and fitted into a groove formed in the end of the arbor T', in such a manner that the latter can slide up and down with the movement of the frame R', and still be retained by the edges of the plate w.

The lever V is attached to a treadle, Z, by rods and cord y, which passes over a pulley, y', fixed in the top rail of the main frame A, as fully indicated in the drawings.

By pressing the foot upon the treadle Z, the auger T is moved forward, and when the pressure is removed, the auger T and arbor T' are thrown back by a coiled-wire spring, 7, placed around the end of the arbor T', upon which it acts with its expansive force, by one of its ends resting against the bearing s', and the other against a collar, v', fixed to the arbor T'.

At the right-hand end of the machine is arranged a cutter-head, W, to be used for backing off spokes, and other purposes. It is fastened to the end of an arbor, K', that turns in bearings 8, supported by the frame R'', which is hinged in like manner to the others, at the back of the machine, to the main frame A, so that it may be lowered and raised. The arbor K' is turned by a belt, M', from the pulley 3 upon the main shaft K. The cutter-head is constructed as shown in the drawings, and furnished with knives 9.

In the end of the arbor, at the centre of the cutter-head W, is fitted a bit, 10, for boring holes in the ends of felloes to receive the dowel-pins, and suitable gauges, 11 and 12, are arranged upon the bed-piece L', between which the end of the felloe is placed while it is being bored.

An adjustable gauge, 13, is also fastened to the bed-piece L', to be used with the cutter-head W. It can be moved back and forward, or swung around to any desired position.

The bed-piece L' is secured, by a hinge, l, to the back part of the main frame A, so that it can be easily raised, to get any parts of the machine beneath.

The swinging frames R, R', and R'', have handles, 14, projecting through the front of the machine, by which they can be raised and lowered. They are retained in position, when raised, by spring-catches 15, that hold them up, and by projections 16, upon the main frame A, that prevent any side-motion, said pro

jections being fitted into spaces cut in the front part of the swing-frames R, R', and R² to receive them, all of which is fully indicated in the drawings.

For boring mortises in felloes, a block, D', is used, having a cylindrical base, E', which fits into the self-centring chuck upon the table B.

The top of the block D' is hollowed, to fit the curve of the felloe F, and has, at the back side, a flange, 17, against which the felloes are placed.

In rear of the flange 17, secured by a set-screw, 18, are three adjustable gauges, the points, 19, 20, 21, of which extend forward to the centre of the felloe F.

The cutter-head g is removed from the spindle E, and a bit, 22, fitted into the hole, t², made for that purpose in the lower end of said spindle.

The operation is as follows:

The machine is set in motion by applying the power to pulley 2, on the main shaft K. Then, to cut the box-seats in hubs, the long lever J is pressed down with the foot, and latched under the right-angled catch J', which operation raises the pulley H, so that the notches on its hub engage with the pins on shaft H, thereby setting it, with the upright spindles C and E, in motion. The hub to be operated on is placed in the chuck upon table B, with its inner or larger end downward, and the handle f drawn toward the front, turning the top rim e and curved ribs e', thereby causing the dogs d to move forward, which seize and hold the hub directly over the centre of the opening in the table B, with its axis in line with the axis of the cutter-heads D and g and spindles O and E. Then, by pressing with the foot upon the treadle G, the spindle C and cutter-head D are raised, and spindle E and cutter-head g are lowered, cutting into the hubs until the flanges n and n' strike the ends thereof. The pressure is then removed from the treadle G, and the spindles and cutter-heads carried back to their former positions by the spring, k, at the top of the spindle E, after which, by moving back the handle f, the hub is removed, and the operation of cutting the box-seats completed.

After the spokes have been driven into the hub, the wheel is placed upon the centre-pin p, at the left-hand end of the machine, said pin being set so that the distance from the centre of the pin p to the saw S is equal to the required radius of the wheel.

By means of its handle 14, the swing-frame R is raised, and the saw brought into working-position. Then, by turning the wheel upon the pin p, the spokes may be all sawed off at the right length.

In lieu of the centre-pin p, a chuck placed upon the chuck-seat N may be used, if desirable, the seat being set at the proper distance from the saw S.

After the spokes have been sawed off, the left-hand spring 15 is drawn back, and the frame R lowered, which takes the saw down out of the way; and, by raising the frame R', the hollow auger is brought up into working-position. The gauge-collar t, upon the arbor T', is set so that it will strike the bearing s', when the tenon is cut to the right length. The spokes are then held by the hand-lever P', by placing the notch r upon the spokes, and pressing it on to the platform P. Then, by pressing the foot on the treadle Z, the hollow auger T is moved forward, and cuts the tenons.

When the collar t strikes the bearing s', the pressure of the foot upon the treadle Z is removed, and the auger T is thrown back by the spring, 7, at the opposite end of the arbor T.

By turning the wheel upon the pin p, each spoke is brought into line, and the operation repeated until the tenons upon all are cut.

To bore the felloes, the cutter-head g is removed from the upright spindle E, and a bit, 22, inserted in the end of said spindle. The bolt 23, that connects the step a, at the lower end of spindle C, to the lever a, is removed, and the lower belt I thrown off from the pulley I, at the back of the machine, thus pre-

venting all operation of spindle C and cutter-head D. The boring-block D' is then arranged in the chuck, as indicated in the drawings, figs. 7 and 8, and the gauge-points 19, 20, and 21 set at the proper distances. One end of the felloe being sawed off square with the saw S, it is placed upon the block D', against the flange 17, with the squared end at the first right-hand gauge-point 20, where it is held, while, by pressing with the foot upon treadle G, the bit 22 is brought down, and, the spindle E being in motion, a hole or mortise, 24, is bored. The pressure is then removed from the treadle G, the bit is drawn out by the spring k, and the felloe is moved along to the right, until the centre of the hole just bored is at the second right-hand gauge-point 21, as indicated by red lines in fig. 8, when the bit is again brought down, boring a second hole or mortise. In like manner, the operation is repeated until the last hole in the felloe is bored, when, without moving it further, the felloe is marked to be cut off at the left-hand gauge-point 19, which completes the operation of boring the holes or mortises.

After the ends of the felloes have been cut off, the holes for the dowel-pins are bored, by inserting the ends of the felloes between the guards 11 and 12, as indicated by red lines, fig. 2, where they are bored by the bit, 10, at the right-hand end of the machine.

The square tenons upon the spokes are backed off, to give the desired draught, by placing them against the gauge 13, upon the table L', where they are shaved off by the knives 9, secured to the cutter-head W, which may also be used for a great variety of other works besides backing spokes.

In lieu of the boring-block used for boring felloes, a flat table may be placed in the chuck at the front of the machine, and, by the use of different bits, the machine may be used for great variety of work.

The motion of the upright spindles C and E is stopped by raising the lever J, which releases the pulley H' from the clutch-pins on the shaft H.

To stop either the upper or lower spindle, the belt which operates it is thrown off from its pulley at the back of the machine.

The arbors Q, T', and K' are stopped by lowering their respective frames, R, R', and R², which loosens their respective belts, and started by again raising them to their working-positions, thereby using no more power than is necessary to run the parts in actual operation.

The self-centring chuck may be used in machines for other purposes than making wheels.

By the foregoing description, it will be seen that we have constructed a machine that will greatly facilitate the putting up of wheels from stock as purchased from the manufacturers—a machine simple in its construction, convenient in its arrangement, and reliable in its operation; one that requires but little power to run it, and is adapted to a great variety of work, thereby rendering it very desirable to persons engaged in the manufacture of wheels and carriages, or other similar kinds of work.

Having described our improvements in machines for making wheels,

What we claim therein as new, and of our invention, and desire to secure by Letters Patent, is—

1. The arrangement of the rim b, which supports and guides the chuck-dogs d, the hooks c', and top rim e, provided with curved ribs e', and handle f, when said parts are constructed and operated substantially as and for the purposes set forth.

2. The combination, with the self-centring chuck, of the spindles C E, with their cutter-heads D g, substantially as and for the purpose set forth.

3. The combination, with the spindles O E, of the levers F a, treadle G, rod b', spring k, and fork i, substantially as and for the purposes set forth.

4. The combination, with lever a and spindle C, of

the step α' and bolt 23, substantially as and for the purposes set forth.

5. The combination, with spindles C E, of lever α , treadle G, rod b' , and shaft H, provided with pulley I, said parts being arranged, in relation to each other, substantially as and for the purposes set forth.

6. The combination, with the platform P, of the slotted table M, provided with hub-supporting device or devices, as stated of the swinging frame R, with the saw S, substantially as and for the purposes set forth.

7. The combination, with the platform P, of the hub-supporting device, sliding hollow auger T, and swivelled hand-lever P', substantially as and for the purposes set forth.

8. The combination, with the sliding arbor T', of the swinging frame R' and lever V, provided with a flanged plate, w, substantially as and for the purposes set forth.

9. The combination, with the arbor T', hollow auger T, and lever V, of the collars t v' and spring 7, arranged and operating as and for the purposes stated.

10. The employment, in connection with the self-centring chuck, of the flanged and concaved block D',

provided with a base E², as and for the purposes set forth.

11. The combination, with the flange 17, on block D', of the gauges 19, 20, 21, as and for the purposes set forth.

12. The combination, with the arbor K', cutter-head W, and dowelling-bit 10, of the gauges 11, 12, and 13, or either, substantially as and for the purposes set forth.

13. The combination, with the swinging frame R² and swing-table L', of the arbor K', cutter-head W, dowelling-bit 10, and gauges 11, 12, and 13, arranged and operating substantially as and for the purposes set forth.

14. A machine for facilitating the manufacture of wheels for carriages, and other purposes, the parts of which are constructed and arranged in relation to each other, and operating substantially as shown and described.
